United States Patent Office

Des. 194,114
Patented Nov. 20, 1962

194,114

TRAY OR SIMILAR ARTICLE

William J. Graham, Gloversville, N.Y.
(R.D. 1, Johnstown, N.Y.)

Filed Dec. 27, 1961, Ser. No. 68,085

Term of patent 14 years

(Cl. D44—10)

Fig. 1

Fig. 2

Fig. 3

I claim:

The ornamental design for a tray or similar article, substantially as shown.
